CLAIM

The ornamental design for a handle for washing machine as shown and described.

DESCRIPTION

1. Handle for washing machine

1.1 : Front perspective view

1.2 : Back perspective view

1.3 : Front

1.4 : Back

1.5 : Left

1.6 : Right

1.7 : Top

1.8 : Reference

The omitted bottom view is a mirror image of the top view; reproduction 1.8 shows a state in use of the claimed design wherein broken lines depict environmental structure and form no part of the claimed design.

1 Claim, 8 Drawing Sheets
